UNITED STATES PATENT OFFICE.

FRANK S. WEAVER, OF MOUNT WASHINGTON, MASSACHUSETTS.

CLOTHES-PIN.

SPECIFICATION forming part of Letters Patent No. 432,809, dated July 22, 1890.

Application filed October 12, 1889. Serial No. 326,820. (No model.)

To all whom it may concern:

Be it known that I, FRANK S. WEAVER, a citizen of the United States, residing at Mount Washington, (Alandar P. O.) in the county of 5 Berkshire and State of Massachusetts, have invented certain new and useful Improvements in Clothes-Pins; and I do declare the following to be a full, clear, and exact description of the invention, such as will enable others skilled in 10 the art to which it appertains to make and use the same, reference being had to the accompanying drawings, and to the letters of reference marked thereon, which form a part of this specification.

15 The special object of my invention is to make a clothes-pin which shall have the spring so secured to the pin that it cannot be loosened by a fall or rough usage.

20 Figure 1 of the drawings is a front elevation of my clothes-pin; Fig. 2, a side elevation, and Fig. 3 a detail perspective view of the spring.

25 In the drawings, A represents a wooden pin having the holes a a near the upper end thereof. Through these holes I pass the two wire ends b b , which are then turned over in opposite directions on the back a' and there made fast, preferably in grooves thereof. I then coil each arm of the wire B, so as to form a 30 spring b' , which shall rest upon the front a' of the pin A. Next I form the reverse convexities b^2 b^5 to make a space b^3 thereunder

for the reception of the line and fold of the garment. Lastly, I upwardly incline the wire arms from the points b^5 b^5 , which rest upon 35 the pin, to the junction or final meeting curve, which constitutes the loop b^4 for raising the spring.

In order to use my invention, the garment and line are held with one hand and the lower 40 end of the pin with the other, when the latter is pulled down until the line lifts the loop and enters the space under the convexities b^2 b^5 , where it is securely held without liability to escape. 45

Having thus described all that is necessary to a full understanding of my invention, what I claim as new, and desire to protect by Letters Patent, is—

The combination, with the pin A, having 50 holes a a near its upper part, of the wire B, having its ends b b passed through said holes and turned over on the back thereof, the coil-springs b' b' on the front of pin, the reverse convexities b^2 b^5 , forming a subjacent space b^3 , 55 and the upwardly-inclined end loop b^4 , as and for the purpose set forth.

In testimony whereof I affix my signature in presence of two witnesses.

FRANK S. WEAVER.
